UNITED STATES PATENT OFFICE.

FREDERICK C. BARGAR, OF COLUMBUS, OHIO, ASSIGNOR TO THE BARGAR MANUFACTURING COMPANY, OF COLUMBUS, OHIO, A CORPORATION OF OHIO.

FIRE-EXTINGUISHER.

1,235,758.

Specification of Letters Patent. Patented Aug. 7, 1917.

Application filed April 10, 1916. Serial No. 90,070.

To all whom it may concern:

Be it known that I, FREDERICK C. BARGAR, a citizen of the United States, residing at Columbus, in the county of Franklin and State of Ohio, have invented certain new and useful Improvements in Fire-Extinguishers, of which the following is a specification.

This invention relates to fire extinguishers and it is directed particularly to the improvement of portable extinguishers employing an extinguishing fluid under pressure.

The main object of this invention resides in the perfection of a structure, the various parts of which are so related that the container, which is preferably made of glass, will not be broken and further, that this container will be relieved of a breaking jar should the extinguisher as a whole be roughly handled or dropped.

My structure is also arranged so that there are no parts which project beyond the sides of the extinguisher as a whole to reduce the likelihood of its becoming caught while being transported. Further, the projections will not become broken so easily when thus located out of danger, for they cannot be engaged during a fall or bump to in turn transfer the shock to the container.

Another object of my invention resides in the combination of an individual or unitary container and its surrounding protector casing, with a slotted sight opening and a pressure gage, whereby the amount of extinguishing chemical and the area of compression chamber may be readily discerned when the sight gage is read in connection with the pressure gage. This arrangement is essential, first, for the reason that a given volume of compression space is necessary to insure the expelling of all of the extinguishing chemical and, therefore, the two fluids may be so proportioned that, when read in connection with the two gages, an adequate amount of one may be supplied as required by the other. The slotted sight gage when used in connection with the interior chemical container, and protector casing is also essential, in that it relieves the expelling pressure in case the container should be broken without shattering the protector casing. In this way, the extinguisher is rendered perfectly safe to handle for, should the chemical container be broken for some

reason or other, the parts of the extinguisher will not be shattered and thrown into the surrounding space because of the internal pressure, for the reason that this pressure is relieved by escaping into the surrounding space through the slotted sight gage.

Still a further object of my invention resides in an arrangement of check valve structure whereby the check valve is held open against the internal pressure of the container as the fluid is being discharged and when the container is held in its proper position. However, should the container be inverted, the structure is such that the check valve will automatically close the passage leading through the nozzle. I have resorted to this type of arrangement for the reason that it is more difficult to confine air or gas than it is a liquid, and also to prevent release of the air or gas should the valve be opened when the extinguisher is in an inverted position which would release the liquid expelling pressure. The arrangement is such that normally, the liquid is in contact with the discharge points and, therefore, the reduction of pressure is less likely than were the inverse true, for, it is easier to pack a joint to make it impervious to liquid than it is to gas or air, but, because of this check valve structure, no matter in which position the extinguisher may be, opening of the nozzle valve causes the outflow of the liquid or nothing.

The preferred embodiment of my invention is shown in the accompanying sheet of drawings, in which similar characters of reference designate corresponding parts, and in which:

Figure 1 is a view in side elevation and partial section of my improved type of extinguisher.

Fig. 2 is a view in side elevation of the exterior of the lower half of the extinguisher taken at right angles from that shown in Fig. 1,

Fig. 3 is a transverse section taken on line 3-3 of Fig. 2,

Fig. 4 is a vertical section taken on line 4-4 of Fig. 1, and,

Fig. 5 is a view in perspective of one of the retaining wires used as a means of connecting the bottle container and the head.

In these drawings, the bottle is shown at 1, it being desirable to use a glass container

as opposed to metal, in that the extinguishing fluid will have no chemical action with it and further, the glass being transparent, it will be easy to determine the fluid level. In addition to this, metal is sufficiently porous to in time allow the escape of the pressure medium while glass is absolutely non-porous and will indefinitely retain a pressure gas. This bottle container is also preferably of 10 the narrow necked type, as is shown at 2 and the extreme end of the neck or, in other words, the mouth portion is provided with an annular exterior shoulder shown at 3 for a purpose to be presently described. This 15 container is surrounded by a metallic casing 4 provided with longitudinal slots 5 at diametrically opposite points by means of which the fluid level may be readily observed and this container is securely packed 20 within the metal shell by means of the packing shown at 6. To enable the entire extinguisher to be readily transported, I have provided the top portion with the handle 7. The lower end of the shell is flared to present 25 a base 8 of approximately the same diameter as the shell, upon which the extinguisher as a whole may be supported.

To the lower end or to the mouth portion of the bottle, there is attached a head which 30 is designated generally by the reference numeral 9, the upper portion of this head being provided with a channel to receive a suitable packing 10 and one leg of this channel is threaded to form the means of attachment of a nut 11. This nut is further provided with an inwardly extending shoulder 12 which shoulder 12 and the glass shoulder 3 are designed to coöperate with a plurality of arcuately shaped retaining wires 13 by 35 means of which the head and the bottle are detachably connected. These retaining wires are made in arcuate sections in order that they may be inserted to their operative position and after they have assumed such 40 position, the nut 11 is turned to draw the parts securely together against the packing 10. This head is provided with a laterally projecting hollow stem 14 onto the outer end of which a pressure gage 15 is secured. An 45 inspection of Fig. 3 will disclose that this gage is, therefore, at all times in communication with the interior of the bottle to give a visual indication of the pressure within. This portion of the head 9 is held 50 in connection with the base 8 by screwing the nut 10 carried by the outer end of the stem 14 down onto a cork washer of the shape shown at 17. A yielding washer structure is used at this and other points 55 where projections carried by the head 9 pass through the shell to give a semi-rigid connection sufficiently yielding to act as a cushion effective when the extinguisher is given a jar or fall. Thus if the upper end of the 60 bottle should be moved slightly by a fall, 65

the head is permitted to also shift slightly by compressing portions of the cork washers, whereas if this head were rigid with the shell, any tendency to move the upper end of the bottle would place all the strain 70 on the bottle neck. This arrangement is also very convenient when assembling the extinguisher. This head 9 is further provided with the passageway shown at 18, which passageway leads to a point to communicate 75 with the discharge nozzle shown at 19. This nozzle is threaded practically throughout its entire length, the rear portion of it being threaded into the head 9 as is shown and the forward portion receiving the nut 20 by 80 means of which the cork washer 21 may be compressed against the base 8 in a manner similar to that described in connection with the gage member. The extreme outer end of the nozzle 19 is also threaded as is shown 85 at 22 in order to readily secure a connection with a tire inflating mechanism in recharging the extinguisher as will be presently related.

The communication of the nozzle with the interior of the container, is controlled by means of the valve shown at 23 which valve is of the conventional type and which may be operated by the handle 24. The lateral projection 25 forming a portion of the head 9 and also forming a portion of the valve structure as a whole, is secured to and packed in connection with the base 8 in the same manner as has been described for the nozzle and gage member. Release of the 100 valve 23 will permit the fluid to enter the vertical passage shown at 26 in Fig. 4, then around the valve, through the passage 18 and out through the nozzle 19.

It will be observed that the container 1 is 105 in an inverted position so that its discharge opening is at the bottom when in its operative position in which manner the extinguishing fluid is maintained in contact with the controlling valve and gage structure and in which position the expelling pressure gas cannot possibly escape by opening of the valve 23 since it is the space above the fluid level which is filled with air compressed to a high degree and upon release of the valve, 110 this air then causes the discharge of the fluid out through the nozzle as has been related. It is much easier to control or confine the liquid to its container when this liquid is in contact with the discharging 115 points than it would be to confine the air or other gases and, therefore, I have arranged the structure so that its normal position is also its operative position. However, to guard against misuse, I have provided a 120 supplemental valve structure or a check valve structure arranged to remain in an open position against the internal pressure when the container is in the position shown in Fig. 1, but which will automatically close 125 130

the outlet passage when the container is moved to an inverted position, in which case the compressed air will be in contact with the discharge parts and will not escape should the release valve be opened. This check valve structure comprises an ordinary tapered valve such as is shown at 27, the underside of which is provided with a guide rod 28 to guide the valve in its vertical movement. The lower side of the valve 27 is formed integrally with an L-shaped rod 29 and the upper end of this rod is pivotally connected at 30 with the weight arm 31. This weight arm 31 is in turn pivotally mounted at 32 in connection with a supporting standard 33 and the weight 34 on the end of this rod when considered in connection with the difference in leverage between it and the pivot connection 30, will hold the valve 27 away from its seat after the discharging valve has been opened and against the internal pressure. However, when the extinguisher as a whole is inverted, this weight acts in a manner to automatically close the check valve, no matter whether there is a slight leakage at this point or not. Further, any liquid confined in the passage 26 will then be held confined by the check valve to further seal a possible source of escape of the gas. I have provided the gage member 15 so that it may readily be determined whether the internal pressure has been reduced through leakage or not.

After the liquid within the container has been discharged, the same may be recharged by removing the plug 35 secured in the lower end of the head 9 and filling the container to the desired level. After this, the plug is replaced and securely wedged against the gasket 36. The extinguisher as a whole is then inverted and the threaded portion 22 of the nozzle attached to a tire pump or air compressor of some type. The valve 23 is then opened and compressed air introduced into the container until the gage 15 shows the proper pressure, whereupon the valve 23 is closed and the extinguisher again righted to bring the liquid into contact with the discharging parts as has been previously related.

What I claim, is:

1. A fire extinguisher comprising an open bottom glass container, a protector shell surrounding said container, a packing between said container and said shell for properly holding said container within the shell, a head secured to the bottom of and in communication with the interior of the container, said head being located within said shell, a controlling valve carried by said head, an operating handle therefor and a discharge nozzle, the valve stem and nozzle projecting from said head and through said shell.

2. A fire extinguisher comprising an open

bottom glass container, a protector shell surrounding said container, a packing between said container and said shell for properly holding said container within the shell, a head secured to the bottom of and in communication with the interior of the container, said head being located within the shell, a controlling valve carried by said head, an operating stem and handle therefor, a nozzle carried by said head, and a pressure gage carried by said head, said nozzle, the valve stem and gage projecting out through the side of the shell.

3. A fire extinguisher comprising an open bottom glass container, a protector shell surrounding said container, a packing between said container and said shell for properly holding said container within the shell, a head secured to the bottom of and in communication with the interior of the container, said head being located within the shell, a nozzle projecting out through the side of the shell from said head, means for yieldingly packing the nozzle in connection with the shell for its passage therethrough, and a regulating valve mechanism for said nozzle.

4. A fire extinguisher comprising an open bottom glass container, a protector shell surrounding said container, a packing between said container and said shell for properly holding said container within the shell, a head secured to the bottom of and in communication with the interior of the container, said head being located within the shell, a valve mechanism carried by said head, a valve handle therefor, a discharge nozzle, and a pressure gage carried by said head and projecting laterally through said shell adjacent its base.

5. A fire extinguisher comprising an open bottom glass container, a protector shell surrounding said container, a packing between said container and said shell for properly holding said container within the shell, a head secured to the bottom of and in communication with the interior of the container, said head being located within the shell, a valve mechanism carried by said head, a valve handle therefor, a discharge nozzle, a pressure gage carried by said head and projecting laterally through said shell adjacent its base, and means for yieldingly packing said nozzle and gage in connection with the shell for its passage therethrough to coöperate with said first named packing for properly holding the container.

6. A fire extinguisher comprising an open bottom glass container, a shell surrounding said container, a packing between said container and said shell for properly holding the container within the shell, a head removably carried by the lower end of said container and located within said shell, a valve, and a stem therefor and a nozzle and

- pressure gage all carried by said head and projecting out laterally through the side of said shell.
7. A fire extinguisher comprising an open bottom container, a shell surrounding said container having a base and reduced in size adjacent the base to present an annular depression, a valve controlling the outlet from said container, and a valve stem, nozzle and pressure gage all projecting out laterally into said annular depression but confined within the outline of the shell proper.
8. A fire extinguisher comprising a container, a nozzle carried by said container, a hand operated valve governing the outflow through said nozzle, a check valve structure interposed between said first named valve and the point of communication of said nozzle with the interior of said container, and means operating in connection with said check valve for holding it open against the internal pressure when said container is in inverted position, and closing it when the bottle is in its reverse position.
9. A fire extinguisher comprising a container, a head secured to said container, a nozzle carried by said head, a hand operated valve governing the outflow through said nozzle, a check valve seat in said head interposed between said first named valve and the point of communication of said nozzle with the interior of said container, a check valve mounted for movement to seat itself on its seat, and a weighted lever for controlling the movement of said check valve arranged to hold the check valve open against the internal pressure when said container is in inverted position and closing it when the container is in the reverse position.
10. A fire extinguisher comprising a single compartment glass container for holding an extinguishing chemical and a pressure fluid, one being a liquid and the other a gas, a pressure indicating means in communication with the interior of said container, and a protector casing surrounding said shell and provided with a sight opening, the pressure indicating means and the sight opening co-operating to give a visual indication of the volume of compression space and pressure relied upon to expel the liquid chemical.
11. A fire extinguisher comprising a single compartment glass container for holding an extinguishing chemical and a pressure fluid, one being a liquid and the other a gas, said container being open at its bottom only, discharging mechanism connect-

ed to the opening in the bottom, a pressure gage communicating with the interior of said container below the liquid level, and a protector casing surrounding said shell and provided with a sight opening which extends above and below the normal liquid level whereby the gage and sight opening co-operate to give a visual indication of the volume of compression space and pressure relied upon to expel the liquid chemical.

12. In a fire extinguisher, a unitary glass chamber for holding compressed air and fire extinguishing fluid, a pressure gage in constant open communication with said chamber, a casing surrounding said chamber and provided with oppositely disposed slots for indicating the amount of fluid and area of compression chamber, and when read in connection with the pressure gage indicates whether or not there is sufficiency of compression to expel the entire contents with required force, a fluid filling opening in the bottom of the chamber and a combined air inlet and fluid exit in the wall of the chamber near the bottom thereof.

13. In a fire extinguisher, a combined fire extinguishing fluid and compressed air chamber, a filling port at the bottom of said chamber and a port also at the bottom of the chamber functioning as an exit port for the contents of said chamber and as an inlet port for the compressed air, and a pressure gage also at the bottom of and in constant open communication with said chamber, whereby the body of said fluid functions as a seal between said ports, pressure gage, and the body of the compressed air.

14. In a fire extinguisher, the combination with a unitary fluid and compressed air holding chamber, of a fluid filling port, a pressure gage at the bottom of and in constant open communication with said chamber, and a port functioning as an inlet port for introducing air into said chamber and as an exit port for expelling the fluid from said chamber, said ports and gage being at substantially the bottom of said chamber, whereby the body of fluid is between the said ports and gage and the body of compressed air and thereby acts as a seal to prevent the air escaping through the joints incident to the connection between the chamber, said ports and gage.

In testimony whereof I affix my signature in presence of two witnesses.

FREDERICK C. BARGAR.
